CEILING BOARD PROP

Romain Couture, Somersworth, N. H.

Application July 28, 1943, Serial No. 496,513

1 Claim. (Cl. 248—354)

This invention relates to a portable prop or support designed for use in supporting "Celotex" or similar ceiling or wall-board material, while the material is being nailed to ceiling beams.

An important object of the invention is to provide a support of this character which may be readily and easily extended or adjusted to different heights, to support the ceiling boards against the ceiling beams, in constructing ceilings of various heights.

Another object of the invention is to provide a support including pivoted arms adapted to be swung outwardly providing a wide supporting surface for contact with the ceiling board being positioned, to hold the ceiling board against buckling or moving, during the nailing or securing operation.

Still another object of the invention is to provide a support which may be folded into a small and compact article to facilitate the storing and transportation of the prop.

With the foregoing and other objects in view, which will appear as the description proceeds, the invention resides in the combination and arrangement of parts and in the details of construction hereinafter described and claimed, it being understood that changes in the precise embodiment of the invention herein described, may be made within the scope of what is claimed, without departing from the spirit of the invention.

Referring to the drawings:

Figure 1 is an elevational view of a prop or support, constructed in accordance with the invention.

Figure 2 is a longitudinal sectional view through the support when in its extended position.

Figure 3 is an elevational view of the support in its folded condition.

Figure 4 is a sectional view taken on line 4—4 of Figure 2.

Figure 5 is a sectional view taken on line 5—5 of Figure 1.

Figure 6 is a sectional view taken on line 6—6 of Figure 1.

Referring to the drawings in detail, the prop or support comprises a lower section 5 and an upper section 6. The lower section 5 embodying a post having a cutout portion extending an appreciable distance inwardly, from the lower end thereof. Secured within the cutout portion of the lower section 5, is a member 7 that has its ends extended beyond the edges of the lower section 5, providing connecting means for the pivoted feet 8 which as shown, are substantially

long. These pivoted feet embody spaced members between which brace bars 9 are pivotally mounted, the upper ends of the brace bars 9 adapted to extend to a point within the upper ends of the cutout portion of the lower section 5, where they engage the shoulders 10 formed at the inner end of the cutout portion, thereby bracing the pivoted feet to hold the pivoted feet 8 in their extended positions.

10 The reference character 11 indicates a foot member which is hingedly connected to the lower end of the lower section 5, by means of the hinge 12. The foot 11 extends to a point under the lower end of the lower section 5 where it has hinged connection with the foot 13 extending laterally at the opposite side of the lower section 5. A hook indicated at 14 is pivotally connected with the lower section 5, and is adapted to hook into the eye 15 secured to the upper surface of the foot 13. Thus it will be seen that due to this construction, when the pivoted feet at the lower end of the lower section 5 are extended, they will be held rigidly against movement, to support the prop in an upright position. It will also be seen that by swinging the feet upwardly to a position as shown by Fig. 3 of the drawings, the feet will be moved into close engagement with the lower section 5 to facilitate storing or transporting the prop.

20 30 The upper section 6 is hollow, and is adapted to receive the lower section 5, as shown by Fig. 2 of the drawings. The reference character 16 indicates a drum which is extended through the upper section 6, near the lower end thereof, the drum 16 being provided with a crank 17 at one end thereof, whereby the drum may be rotated. A cable indicated at 18 has one of its ends wound on the drum 16, the opposite end thereof being connected to the lower section 5, at the upper end of the lower section as shown by Fig. 2. Thus it will be seen that as the crank 17 is rotated to wind the cable 18 on the drum 16, the upper section 6 will be elevated for supporting a ceiling board to be nailed to ceiling beams in building construction.

35 40 45 Notches 19 are formed in one edge of the lower section 5, and are adapted to be engaged by the pivoted plate 20 which is secured at the lower end of the upper section 5. When the upper section 6 has been moved to its proper supporting position, the plate 20 is moved to engage the notch 19, falling opposite to the inner end thereof, thereby providing a support for the upper section and article or ceiling board supported at the upper end thereof.

As clearly shown by Fig. 5 of the drawings, the upper section 6 is rectangular in cross section and at each side face of the upper section at a point adjacent to the upper end of the upper section, is an arm 21, the arms being so arranged that they extend at right angles with respect to each other and the upper surfaces of the arms present a supporting surface to be positioned against the ceiling board which is to be attached to the ceiling beams of the building. When the prop or support is in its folded condition, these arms 21 extend upwardly in substantially parallel relation with respect to each other. When the arms are moved to their active or supporting positions, they are moved to the position shown by Fig. 1 of the drawings, the lower edges of the arms 21 resting on the upper ends of the stops 22, so that the arms will be firmly held in their horizontal supporting positions.

From the foregoing it will be seen that due to 20 the construction shown and described, I have

provided a support or prop which may be used in supporting ceiling boards in their proper positions while they are being nailed to the ceiling beams of a building, to the end that the ceiling board will be held against buckling or bending, during the nailing operation.

What is claimed is:

A ceiling prop comprising telescoping upper and lower sections, the lower section being formed with openings near the lower end thereof, presenting a shoulder, pivoted feet secured to the lower section, bars pivotally connected with the feet and adapted to move within the opening of the lower section, the upper ends of said bars adapted to engage the shoulder, holding the device in an upright position, and pivoted arms at the upper end of the upper section, said arms being adapted to swing to horizontal positions for supporting an article thereon.

ROMAIN COUTURE.
